FIG.1

FIG.2

FIG.3

INVENTOR
H. W. S. HOY,
BY J. R. DAIRIE
ATTY.

UNITED STATES PATENT OFFICE

HENRY WILLIAM SEW HOY, OF DUNEDIN, OTAGO, NEW ZEALAND

GRAMOPHONE

Application filed August 13, 1926. Serial No. 129,013.

This invention relates to mechanically operated musical instruments commonly known as gramophones, phonographs and the like, for reproducing sounds.

5 The object of my invention is to eliminate vibration, by providing an amplifier having the advantages of a full floating horn in that the outlet of the tone arm is inverted in order to render the cabinet housing the said tone arm, and the horn applicable to a combination dinner waggon, table or the like furnishing.

10 A further object is to form a sound box having the said amplifier disposed in communication therewith at the mouth and at the centre of vibration of one or more sides of the amplifier. In the model experimented with a sound post similar to that used in violin construction was adopted, and was positioned 15 at about the centre of vibration of the top and bottom of the amplifier, and between it and the top and bottom of the sound box, as indicated in the accompanying drawings.

15 Referring to the drawings accompanying this specification,

Figure 1 is a perspective view of a combination gramophone and dinner waggon constructed in accordance with my invention.

Figure 2 is a sectional plan view through 20 2—2 in Figure 1.

Figure 3 is a sectional elevation through 25 3—3 in Figure 1.

There is a cabinet preferably composed of eight sides, 1, 1A, 1B, 1C, 1D, 1E, 1F, 1G, the 30 sides 1A, 1B, 1C, 1D, 1E, forming permanent sides of the cabinet, and support at their upper and lower extremities the top 2 and bottom 3 respectively. The top and bottom extends sideways on either side of the cabinet 35 to be rigidly supported by means of the columns 4. On either side of the cabinet are the super-imposed shelves 5 made fast at one end to the cabinet and at the other to the column 4. The bottom 3 is mounted on suitable castors 6 and handles 7 are attached to either end of the top 2, making the cabinet 40 portable.

The cabinet is divided horizontally into 45 three compartments. The bottom compartment 8 houses the motor 9 and may be pro-

vided with fittings for storing disc records. The central compartment 10 houses the rotating disc 11 and tone arm 12 of the machine. Three of the sides namely 1, 1G and 1F of the central compartment 10 are hinged 55 at 13 to the cabinet to open for the convenience of getting at the tone arm 12 for inserting needles, and to replace records on the rotating disc 11.

The upper compartment 14 contains the 60 horn or amplifier, which has the advantage of a full floating horn, the inner end 15 of which is bent at right angles to project downwardly through the partition 16 between the upper compartment 14 and the central compartment 10, the hole in the partition 16 being 65 large enough to ensure clearance for the said downwardly projecting part 17 of the horn. The end of the downwardly projecting part 17 is connected to the inverted tone arm 70 12, which is suitably suspended to enable it to swivel in the ordinary manner.

The horn is composed preferably of thin timber and comprises four sides, a top 18 and a bottom 19 slightly bent along the length 75 of the horn, the convexity formed being on the inside thereof. There are two sides 20 and 21 which embrace the top and bottom 18 and 19 on either side to form a rectangular shaped horn or amplifier; the mouth of the said horn 80 embracing the three sides 1, 1F, and 1G of the cabinet which sides are operable upon hinges to open or/and to close.

A base bar 22 is disposed within the compartment 14 and is adapted to lie along the 85 top of the amplifier between the top 2 of the cabinet and the top 18 of the amplifier, and is glued or otherwise secured in place to rigidly support the said top 18 of the amplifier. A sound post 23 placed perpendicular to the base bar 22 at about the centre of gravity of the top 18 of the amplifier is in contact with the top 2 of the cabinet and the base bar 22.

There is a sound post 24 which is preferably adjustable and provided with a threaded portion 25, which is adapted to fit an internally threaded hole in the partition 16. The portion 26 is adapted to press against the bottom 19 of the amplifier at about the 100

centre of gravity thereof and is necessarily perpendicular to the said bottom 19. An octagonal head fashioned on the said adjustable sound post is provided for adjusting the post to add or/and lessen the tension upon the bottom 19, for the purpose of toning the amplifier. The sides 1, 1G, and 1F, of the top compartment 14 are preferably of ornamental design having fretwork panels lined 5 with silk, gauze or the like materials, and the sides 20 and 21 of the amplifier may be also ornamented with fretwork or have a monogram cut therein to act in a certain degree as a sounding board when the space at 10 the rear of the horn, which is embraced by the five sides 1A, 1B, 1C, 1D, and 1E, of the cabinet, may be rendered to some value as 15 an amplifier.

What I claim as new and desire to secure 20 by Letters Patent is:—

1. A sound-reproducing machine, comprising a cabinet having an elongated base, a corresponding top, pillars rising from the base and supporting the top, upper and lower 25 shelves arranged in spaced relation to each other and to the top and bottom to provide lower, intermediate and upper spaces, the shelves being connected to and supported by the pillars, a vertical wall extending from 30 the bottom of the cabinet to the lower shelf and formed in part to provide doors, said wall defining a lower compartment of the full width but of less length above the bottom, a wall extending from the intermediate 35 to the upper shelf and formed to provide doors, said last named wall forming an intermediate compartment aligned with and corresponding in sectional dimensions to the lower compartment, a motor housed in the 40 lower compartment, a turn table mounted in the intermediate compartment and operated by the motor, and an amplifier secured between the upper shelf and the cabinet top, a means for varying the tone of the amplifier 45 mounted in the upper shelf and bearing against the amplifier, and a reproducer in communication with the amplifier and arranged in the intermediate compartment.

2. A sound-reproducing machine, comprising 50 a cabinet having an elongated base, a corresponding top, pillars rising from the base and supporting the top, upper and lower shelves arranged in spaced relation to each other and to the top and bottom to provide lower, intermediate and upper spaces, the shelves being connected to and supported by the pillars, a vertical wall extending from 55 the bottom of the cabinet to the lower shelf and formed in part to provide doors, said 60 wall defining a lower compartment of the full width but of less length above the bottom, a wall extending from the intermediate to the upper shelf and formed to provide doors, said last named wall forming an intermediate 65 compartment aligned with and

corresponding in sectional dimensions to the lower compartment, a motor housed in the lower compartment, a turn table mounted in the intermediate compartment and operated by the motor, and an amplifier secured between the upper shelf and the cabinet top, 70 said amplifier having a width at its outlet end corresponding to the length of the said compartments and secured at such outlet end to the top and upper shelf, an adjustable sound post mounted in the upper shelf and bearing against the amplifier, said post being accessible from the intermediate compartment for adjustment, and a reproducer in communication with the amplifier and arranged in the intermediate compartment. 75

In testimony whereof I have hereunto set my hand.

HENRY WILLIAM SEW HOY.
